J. L. BROWN.
PIPE CLAMP.
APPLICATION FILED MAY 15, 1922.

Patented Oct. 3, 1922.

UNITED STATES PATENT OFFICE.

JOSEPH L. BROWN, OF ALPINE, TEXAS.

PIPE CLAMP.

Application filed May 15, 1922. Serial No. 561,098.

To all whom it may concern:

Be it known that I, JOSEPH L. BROWN, a citizen of the United States, residing at Alpine, in the county of Brewster and State 5 of Texas, have invented certain new and useful Improvements in Pipe Clamps, of which the following is a specification, reference being had to the accompanying drawings.

This invention relates to improvements in 10 pipe clamps and more particularly to a pipe clamp for use upon decks of drilling rigs for holding the casing in the desired position.

An important object of the invention is 15 to provide a device of this character, the clamping action of which is distributed about the casing in a manner that prevents collapsing thereof by the clamps.

A further object of the invention is to 20 provide means whereby the rotation of the casing when gripped by the clamps is prevented.

A further object of the invention is to 25 provide a clamp, the jaws of which are provided with gripping teeth so constructed that not only is rotation of the casing prevented, but the teeth will clear themselves from any cuttings gathered from the pipe in gripping the same.

30 A still further object of the invention is to provide a device of this character which may be controlled by the foot in order that the hands of the operator may be left free to engage a control or guy-rope or the control of a hoisting engine.

These and other objects I attain by the arrangement shown in the accompanying drawings, wherein for the purpose of illustration is shown a preferred embodiment of 40 my invention and wherein like reference characters designate like parts throughout.

In the drawings:—

Figure 1 is a perspective view of a pipe clamp constructed in accordance with my 45 invention;

Figure 2 is a transverse sectional view therethrough;

Figure 3 is an enlarged detailed sectional view showing one manner of preventing 50 movement of the stationary jaws;

Figure 4 is a front elevation of the movable jaw; and

Figures 5 and 6 are front elevations of the stationary jaws.

55 Referring now more particularly to the drawings, the numeral 10 indicates a plu-

rality of arcuately curved frame members, each of which is provided upon its ends with outwardly directed flanges 11. The numerals 13, 14 and 15 designate clamping 60 jaws, the clamping jaws 13 and 14 being hereinafter referred to as stationary clamping jaws and the clamping jaw 15 as a shiftable clamping jaw. The clamping jaws 13 and 14 are clamped intermediate the flanges 65 of the adjacent frame sections 10 by means of bolts 12. By loosening these bolts these jaws may be adjusted to any desired position and such positioning, as will herein-after more fully appear, will permit accom- 70modation of varying sizes of pipe by these jaws.

The shiftable jaw 15 is pivoted intermediate the flanges 11 of the adjacent sections 10 by means of a pivot bolt 17, which bolt 75 forms a mounting for a yoke 18 straddling the shiftable jaw 15. This jaw is provided with a foot treadle tail piece 15^a and between this foot treadle and the yoke 18 a tension spring 19 is connected, tending to 80 force the jaw 15 toward the jaws 13 and 14 and accordingly to force a piece of pipe extending between the jaws 13 and 14 into engagement with these jaws.

Each of the jaws 13, 14 and 15 has its 85 gripping face 20 in the form of a cam curved so that by adjusting the jaws about the pivots thereof the adjacent faces thereof may be spaced apart the desired distance. These adjacent faces are provided upon their 90 surfaces with teeth 21 for gripping the pipe, the teeth of the stationary jaws 13 and 14 being angularly disposed and the teeth of the shiftable jaw 15 being disposed transversely of the jaw. In providing the jaws 95 13 and 14 with the angular teeth these are oppositely angled.

In the use of my device when it is desired to clamp the casing by the use of the clamp, one of the sections 10 may be removed and the device reassembled about the casing upon the deck of the rig or upon the ground, as the case may be. The spring 19 by its engagement with the shiftable jaw will force the shiftable jaw into engagement 105 with the casing and accordingly force the casing into engagement with the jaws 13 and 14. A three point grip being provided, collapsing of the casing is prevented, this collapsing often occurring where the casing 110 is gripped upon opposite sides.

When it is desired to shift the casing

through the clamp it may be readily disengaged by placing the foot upon the treadle 15 and withdrawing the shiftable jaw 15 from the casing. At this time the casing 5 may be raised or lowered for any engagement of the jaws therewith, being held out of engagement with the jaws 13 and 14 by means of a guy rope or the like if so desired.

10 While the clamping engagement of the bolts 16 through the medium of the flanges 11 against the stationary jaws 13 and 14 will ordinarily be sufficient to prevent shifting of these jaws, this clamping action may 15 be further reinforced by placing between the tail portions 22 of these stationary jaws and the deck 23 of the rig a wedge 24. This will effectually prevent opening of the jaws due to engagement thereof by the pipe, and 20 movement of the jaws to their closed position will of course be prevented by the pipe itself.

From the foregoing it is believed to be 25 obvious that a clamping device constructed in accordance with my invention will effectually prevent rotation of the pipe since the opposite inclination of the teeth of the stationary jaws will tend to rotate the pipe in opposite directions, thereby holding it stationary and by reason of the fact that the provision of the foot operated treadle upon the shiftable jaw permits the operator to have his hands free to control the movement of the pipe through the clamp. It will 35 furthermore be obvious that the construction hereinbefore set forth is capable of some change and modification without materially departing from the spirit of my invention and I accordingly do not limit 40 myself thereto except as hereinafter claimed.

What is claimed is:—

1. In a pipe clamp, three concentred pivoted clamping jaws, means for securing

two of the jaws in adjusted positions upon the pivots thereof, and means yieldably forcing the third jaw into engagement with the first named jaws. 45

2. In a pipe clamp, three concentred pivoted clamping jaws, means for securing two of the jaws in adjusted positions upon the pivots thereof, and means yieldably forcing the third jaw into engagement with the first named jaws, the first named jaws being provided upon the gripping faces thereof with oppositely inclined teeth. 50

3. In a pipe clamp, three concentred pivoted clamping jaws, means for securing two of the jaws in adjusted positions upon the pivots thereof, means yieldably forcing the third jaw into engagement with the first 60 named jaws, the first named jaws being provided upon the gripping faces thereof with oppositely inclined teeth, and a foot treadle for withdrawing said third jaw against the action of said means. 65

4. In a pipe clamp, a elastic yoke, the sections of which are arcurate in formation and provided upon the extremities thereof with outwardly directed flanges, concentred clamping jaws pivotally mounted intermediate the flanges of said sections, each having a cam gripping face provided with gripping teeth, one of said jaws having a tail piece forming a foot treadle and having means engaged with said tail piece normally urging the jaw toward the common center of the jaws, the teeth of the last named jaw extending transversely of the jaw and the teeth of the remaining jaws being inclined, the teeth of one jaw being inclined oppositely to the teeth of the next adjacent jaw, and means for holding the last named jaws in adjusted positions. 75

In testimony whereof I hereunto affix my signature.

JOSEPH L. BROWN.
